UNITED STATES PATENT OFFICE.

BENJAMIN A. ARMSTRONG, OF NEW YORK, N. Y.

DRAWER-FRONT.

SPECIFICATION forming part of Letters Patent No. 224,066, dated February 3, 1880.

Application filed August 16, 1879.

To all whom it may concern:

Be it known that I, BENJAMIN A. ARMSTRONG, of New York city, in the State of New York, have invented certain new and useful Improvements in Drawer-Fronts, of which the following is a specification.

The invention relates to certain metal strips which serve as means for confining the rings or drawer-pulls. They allow, better than heretofore, the employment of glass as the material for the front. The metal parts may be cheaply constructed and easily applied.

The invention is intended more particularly for the shallow drawers in cases for exhibiting fancy articles, as cotton, silk, &c., on spools; but it may be used in a great variety of situations.

It will be understood that one of the fastenings is applied at each end of the drawer-front, and serves not only to attach the ring or other pull by which the drawer is drawn out, but also to strongly hold the front plate, whether of glass or other material, to the sides. The latter, it will be understood, are of wood.

Accompanying drawings form a part of this specification, and represent what I consider the best means of carrying out the invention.

Figure I is a perspective view of part of drawer with my improvements applied thereto. Fig. II is a partial internal view of the same. Fig. III represents a plan view of the fastening separately previous to being applied to a drawer.

Similar letters of reference indicate like parts in the figures.

A is the bottom, B B the sides, and C the front, of the drawer. The front C is of glass. The sides B and bottom A are of wood.

D D', &c., are peculiarly-shaped pieces of sheet metal, cut by dies or otherwise from a flat plate in the form indicated in Fig. III, and bent at right angles along the lines *a a b b* into the form shown clearly in Figs. I and II. A description of one of these attachments will suffice for both. One is placed at each side of the front.

E is a ring serving as a drawer-pull. It is inserted through holes in the metal D, so as

to form a firm attachment, with liberty to turn down when the pull is not required.

I will designate some of the parts of the metal by additional marks, as D' D². The front part or main face is marked simply D. The parts which form the top and bottom of the device, and which extend across the thickness of the front C at the top and bottom respectively, are marked D'. The parts which extend upward and downward on the back face of the front piece, C, are marked D², and the additional part, which extends inward along the inner face of the side B, is marked D³. Each part D³ has a hole, d³.

In applying my parts together the clasps D are placed in position on the front piece, C, and caused to fit snugly, being bent, by machinery or otherwise, into the correct form without bruising or destroying the metal; then, on applying the front with these attachments in their proper position, the whole is secured by nails or screws G, inserted into the sides B through the holes d³.

The front C is prevented from becoming displaced endwise by being received into recesses b in the front of the sides B of the drawer.

If preferred, however, extensions may be made, extending backward so as to cover the ends of the front C, to prevent its sliding endwise.

The details may be varied. The fronts may be made of other material than glass.

I claim as my invention—

As an improvement in drawers for show and other purposes, the drawer attachment described, composed of the front piece, D, top and bottom bends, D', inner face extensions, D², the side extensions, D³, and fastenings G, in combination with the front plate, C, sides B, and bottom A, as herein specified.

In testimony whereof I have hereunto set my hand this 13th day of August, 1879, in the presence of two subscribing witnesses.

BENJ. A. ARMSTRONG.
